UNITED STATES PATENT OFFICE.

JONATHAN LUCAS, OF SAVANNAH, GEORGIA, ASSIGNOR TO LUCAS-LAMBORN LOOM CORPORATION, OF NEW YORK, N. Y., A CORPORATION OF NEW YORK.

AUTOMATIC STOP MECHANISM FOR LOOMS.

Original application filed May 7, 1924, Serial No. 711,581. Divided and this application filed February 15, 1927. Serial No. 168,255.

The invention relates to looms and more particularly to electrically controlled looms and has for its object to provide a simple and novel mechanism whereby the operation 5 of the loom is automatically stopped in an efficient manner each time a filler thread breaks. Other more specific objects will appear from the description hereinafter and the features of novelty will be pointed out 10 in the claims. The present application is a division of another application filed by me in the United States Patent Office on May 7, 1924, Serial No. 711,581.

In the accompanying drawings, which 15 show an example of the invention without defining its limits, Fig. 1 is a front elevation of a loom embodying the invention; Fig. 2 is a fragmentary front view illustrating the automatic stop mechanism, and Fig. 3 20 is a plan view, on an enlarged scale, of the shuttle shown in Fig. 2.

The loom may be of any suitable construction and in its illustrated form comprises a support or frame 15 of conventional type 25 provided with guiding means upon which the reciprocating elements of the shuttle operating mechanism are guided in their operative movements. As shown in Fig. 1 the guiding devices referred to consist of a plurality of rollers 16 and 16^a arranged in spaced upper and lower series and journaled upon suitable portions of the frame 15, and serve as guides for travelling carriers 17 and 17^a which are arranged to be reciprocated 30 upon the rollers 16 and beneath the rollers 16^a as clearly shown in Fig. 1.

The mechanism whereby the carriers 17 and 17^a are moved toward and away from each other from one extreme position to another 40 may be of any suitable type and, as shown, may comprise a pair of rocking arms 18 pivoted at 19 upon the frame 15 and connected, at one end by means of links 20, with the carriers 17 and 17^a respectively. The 45 other ends of said rocking arms 18 are connected, by means of connecting rods 21 with oppositely disposed cranks 22 forming part of a crank-shaft 23 journaled on the frame 15. The shaft 23 carries a pinion 24 which 50 meshes with a gear 25 fixed upon a counter-shaft 26 also journaled on the frame 15 and operated with a source of power, either elec-

trically actuated such as an electric motor or electrically controlled in some other way.

The carriers 17 and 17^a are each provided 55 with supporting means for the shuttle, which means as shown in Figs. 1, and 2, may comprise fingers 27 and 27^a located in pairs respectively upon said carriers 17 and 17^a, and projecting toward each other. Each 60 pair of fingers 27 and 27^a is constructed and arranged to extend along opposite sides of the shuttle 28, or in other words to straddle the same from opposite directions, and to constitute a support for said shuttle and accordingly 65 may project between flanges 29 suitably located upon the opposite longitudinal sides of said shuttle 28. The arrangement is such that the shuttle is carried alternately by the fingers 27 and 27^a and conveyed 70 thereby over its operative paths. The shuttle 28 may be of any approved construction and in the illustrated form includes transverse walls provided with recesses 30 in which the trunnions 31 of the bobbin 32 75 are rotatably and removably accommodated; the bobbin 32 carries a supply of the weft or filler thread ^a.

In the construction being described, the shuttle 28 is positively coupled to or connected with the shuttle actuating means and disconnected therefrom at predetermined points in its operative paths. The means whereby this positive connection between the shuttle and its operating mechanism is 80 maintained and the disconnection is brought about in alternate sequence may be of different structural characteristics, such as for instance illustrated in the several forms included in the application of which this is a 85 division.

The loom also includes two sets of harness of any customary type and consisting for instance of frames 33 in which the usual heddle wires are supported; the latter carry 90 the warp threads which are arranged in two sets in the well known manner and are manipulated by the harness so as to provide the usual shed through which the shuttle 28 passes. The frames 33 are carried by rods 100 34 connected together in pairs by means of cross-members 35 and properly supported for vertical reciprocation in the loom. In the illustrated example, the mechanism

whereby this reciprocation is effected comprises a double-faced cam 36 having duplicate cam grooves 37 arranged in reversed relation to each other upon its opposite 5 faces; these grooves 37 accommodate rollers 38 rotatably mounted upon the cross-members 35 and serving to transmit the mechanical movements of said cam 36 to the rods 35 and the frames 33 carried thereby. As 10 shown in Fig. 1 the arrangement is such that the cam grooves 37 will raise and lower the frames 33 in alternate sequence so as to reverse the positions of the two sets of warp threads in the customary manner.

15 In operation power is applied to bring about a rotation of the shaft 26 and consequently a rotation of the cam 36; the latter, by means of its grooves 37 and the rollers 38, causes a vertical reciprocation of the two 20 sets of harness 33 in alternate sequence and thus manipulates the two sets of warp threads to provide the shed for the shuttle 28 to pass through as will be set forth hereinafter.

25 As the shaft 26 is driven in the indicated manner, the gears 25 and 24 will transmit power to the shaft 23 whereby the oppositely disposed cranks 22 will be operated, and by alternately pulling and pushing upon the 30 connecting rods 21 will rock the arms 18; this will alternately push and pull the links 20 and consequently will move the carriers 17 and 17^a toward and away from each other on the rollers 16 from extreme outer positions to extreme inner positions and vice 35 versa. In this way the shuttle 28 is passed backward and forward through the shed of warp threads and the filler threads are progressively laid as the weaving proceeds. It 40 will be understood that the harness frames 33 are operated in synchronism with the shuttle 28 so that upon each passage of the shuttle through the shed, the harness is operated to reverse the positions of the two sets 45 of warp threads and the customary beater is actuated to pack the filler thread.

In order to automatically stop the operation in case the filler thread *a* breaks, the following arrangement is provided. As 50 shown in Figs. 2 and 3, the thread *a* passes from the bobbin 32 beneath a resilient finger 39, which is carried by or forms part of an arm or lever 40 pivoted at 41 upon the shuttle 28. The one end of the arm or lever 55 40 is provided with a projection 42, movable adjacent to one of the transverse walls of the shuttle having an aperture or opening 43, the other end 44 of said arm being movable in the slot or opening 45 of another 60 transverse wall of said shuttle. Upon opposite ends of the frame 15, sliding rods 46 and 46^a are mounted, said rods being connected with switch arms 47 and 47^a respectively; the latter are pivoted at 48 upon the 65 frame 15 and each have one end normally

in engagement with contact members 49 forming part of an electric circuit 50 which includes also the electrical controlling means such as the motor 51 whereby the loom is driven. As shown in Fig. 2, the circuit 50 further includes the switch arms 47 and 47^a.

As long as the thread *a* remains unbroken, the arm 40 will be held in the position shown by solid lines in Fig. 2 in which the rod 46 simply passes through the aperture 43 each time the shuttle 28 reaches its extreme left-hand position, while the rod 46^a simply passes above the end 44 of the arm 40 each time the shuttle reaches its extreme right-hand position in Fig. 2. Should the thread *a*, however, become broken and the tension thereon consequently released, the arm 40 being overbalanced toward its one end will assume the position shown by dotted lines in Fig. 2. In this position, the projection 42 is located in registry with the aperture 43, while the end 44 is positioned in the upper portion of the slot 45. If the shuttle at the time of the breakage is moved toward the left in Fig. 2, the projection 42 will finally engage the end of the rod 46 and slidably shift the latter toward the left to move the switch arm 47 to the position indicated by dotted lines in Fig. 2 in which its end is disconnected from the contact 49 and the electric circuit 50 consequently broken; if, at the time of the breakage the shuttle is moving toward the right in Fig. 2, the end 44 of the arm 40 will engage the rod 46^a and likewise slidably shift the latter to swing the switch arm 47^a to the dotted line position in Fig. 2, in which it is disconnected from the contact member 49 and the circuit 50 accordingly is broken. In either case, stoppage of the loom is brought about the moment the shuttle reaches either one of its extreme outer positions so that damage resulting from the broken filler thread is prevented.

The automatic stop mechanism is constructed and arranged to operate with a maximum of efficiency and to reduce the danger of losses due to breakage necessitating shut downs, to a minimum.

Various changes in the specific forms shown and described may be made within the scope of the claims without departing from the spirit of my invention.

I claim:

1. In a loom including an electric controlling circuit, the combination of harness whereby a shed of warp threads is provided, a travelling shuttle carrying a supply of filler thread, means for passing said shuttle through said shed to place the filler thread in position, a lever on said shuttle, clamping means on said lever whereby the latter is connected with said filler thread and is held in an inoperative position as long as said filler thread is under tension, said lever as-

suming an operative position when the filler thread breaks, and switching means adapted to be acted upon directly by said lever when in its operative position to break the electric circuit and stop the loom.

2. In a loom including an electric controlling circuit, the combination of a frame, a harness whereby a shed of warp threads is provided, a shuttle carrying a supply of 10 filler thread, means for reciprocating said shuttle through said shed to place the filler thread in position, a lever pivotally mounted on said shuttle, means on said lever whereby the latter is connected with said 15 filler thread and held in an inoperative position as long as said filler thread is under tension, said lever assuming an operative position when said filler thread breaks, a switch in said electric circuit, and a rod slidably mounted on said frame and arranged 20 to be engaged by said lever when the latter is in its operative position, and slidably pushed to throw said switch and break the electric circuit.

- 25 3. In a loom including an electric controlling circuit, the combination of a frame,

a harness whereby a shed of warp threads is provided, a shuttle carrying a supply of filler thread and provided with openings at its opposite ends, means for reciprocating 30 said shuttle through said shed to place the filler thread in position, a lever pivotally mounted on said shuttle, a resilient finger on said lever whereby the latter is clamped to said filler thread and held thereby in an 35 inoperative position in which the opposite ends of said lever are out of registry with said shuttle openings, said lever assuming an operative position with its opposite ends 40 in registry with said openings when said filler thread breaks, switch arms on said frame and located in said electric circuit, and rods slidably mounted on said frame in registry with said shuttle openings, and 45 adapted to be engaged respectively by the opposite ends of said lever, when the latter is in its operative position, and slidably pushed to throw the co-operating switch arm and break the electric circuit.

In testimony whereof I have hereunto set 50 my hand.

JONATHAN LUCAS.
